STEAM SUPERHEAT CONTROL BY AUTOMATIC AND EXTENDED-RANGE MEANS

Harvey C. Mittendorf, East Orange, N. J., assignor, by mesne assignments to Combustion Engineering-Superheater, Inc., a corporation of Delaware

Application April 1, 1948, Serial No. 18,337

13 Claims. (Cl. 122—479)

1

This invention relates to means for regulating the temperature of steam leaving the superheaters of conventional steam generators, and it has particular reference to an improved control of the superheated steam temperature through a unique automatic variation in the temperature of the heating gases which enter the superheater and also by a novel combination with such gas-temperature variation of bypassing a portion of the heating gases around the superheater.

In the operation of present-day steam generating units (particularly at high steam pressures and temperatures) that are equipped with built-in superheaters, it is well known that the temperature of the superheated steam varies with fluctuations in generator steam output. Thus, when the superheater is of the convection type (as distinguished from the radiant type) a reduction of superheat occurs with a reduction in steam output and an increase of superheat accompanies an increase in output. Because this is undesirable (a substantially constant steam temperature at the superheater outlet typically is required over a wide range in generator capacity), various means have been devised to correct for these steam temperature variations.

One early-proposed method is to by-pass a portion of the heating gases around the convection superheater when the steam temperature undesirably rises and thereby correctively lower the temperature by reducing the flow of gases over the superheater, and when the superheat temperature undesirably falls to cut down the by-pass flow with resultant corrective temperature raising.

Another more recently devised and even more satisfactory method of correctively adjusting the superheated steam temperature is to cause a variation in the heat absorption within the furnace from the fuel burned therein so that the gases passed over the superheater surface are at a temperature capable of producing the desired degree of superheat. A method of this nature as disclosed in the patent to Kreisinger et al. No. 2,363,875 of November 28, 1944, entitled "Combustion Zone Control" provides for the physical raising or lowering of the furnace flame body over a considerable distance to make use of more or less heat absorption surface in the furnace and thereby effect wide range control over the temperature of the combustion gases leaving the furnace and passing over the superheater.

Kreisinger's so called "tilting burner" method

55

has met with wide commercial success particularly in installations (public utility and other) where high capacity (from several hundred thousand to over one million pounds of steam per hour) and high temperature (as 700° F. and above) generating units are employed. But, past practice in effecting necessary adjustments in the burner tilt has been to use a manual rather than an automatic system of control; moreover, it has in certain installations been found desirable to supplement the tilting burner facilities by gas bypass means in order most effectively to meet superheat temperature variations which prove exceptionally wide.

15 Accordingly, an important object of this invention is to provide automatic control means responsive to the superheated steam temperature and effective to adjust the heat absorption within the furnace (tilting burners) in advantageous and commercially satisfactory ways.

Another object is automatically to control a by-passing of furnace gases around the superheater (by-pass damper) in comparably advantageous manner.

25 A further object is to provide an improved method for obtaining the desired steam temperature from the superheater by regulating both the heat absorption within the furnace and the by-passing of furnace gases around the superheater.

A still further object is to coordinate the burner tilting means with the gas by-pass means in such a way that the temperature control ranges of the two are directly additive and otherwise advantageously related.

35 Other objects and advantages will become apparent from the following description of illustrative embodiments of the invention when taken in conjunction with the accompanying drawings wherein:

Figure 1 is a sectional elevation of a steam generator and associated convection superheater together with tilting burner and gas by-pass facilities effective individually and jointly to control superheated steam temperature;

Figure 2 is a reduced-scale section on line 2—2 of Figure 1 showing one way in which the generator furnace's fuel burners may satisfactorily be arranged;

Figure 3 is an enlarged vertical sectional view through one of those generator fuel burners showing one arrangement for vertically tilting the streams of fuel and air directed thereby into the furnace;

Figures 4a—b—c indicate how the tilting burn-

ers may be adjusted respectively to locate the burning fuel flame at lowered, intermediate and raised positions in the furnace combustion chamber;

Figure 5 is a diagram of electrical circuits organized in accordance with my invention to effect an automatic positioning of the tilting burners in a way which holds the superheated steam temperature substantially constant;

Figure 6 is a similar circuit diagram organized to extend my novel automatic regulation to the by-pass damper and arranged to apply required positioning adjustments first to the tilting burners as a primary control and then to the damper as a secondary or range-extending control; and

Figure 7 is a similar electrical diagram differing from Figure 6 in that primary control is effected by the by-pass damper (instead of the burners) and secondary control by the tilting burners (instead of the damper).

The illustrative steam generator to be benefitted

The drawings hereof show my automatic control improvements applied to a steam generator represented in Figure 1 as comprising a furnace A fired by burners 9 and heating a boiler B equipped with a superheater S. Boiler furnaces of this general design (and having a wide range of steam output, pressure and temperature ratings) have already been extensively adopted for such uses (high-capacity and other) as supplying the turbines of electrical generators in power stations, providing steam for the central heating of business and residential districts, and supplying steam for industrial needs.

For facilitating description it will be assumed that the represented boiler furnace has a rated generating capacity (at 100% full load) of 400,000 pounds of steam per hour; a rated operating pressure of 500 pounds per square inch, which establishes the steam saturation temperature at 470° F.; and that for all generator loadings (below, at and above 100% rated) it is desired to hold the superheated or total steam temperature substantially constant at 750° F.

Such assumed values are obviously illustrative rather than restrictive; for as the description proceeds it will become evident that my superheat control improvements (automatic and extended range) also are useable with boiler furnaces of other capacities, characteristics and designs. Particular benefit from these improvements is received by high pressure (typified by up to 1800 p. s. i. and above), high steam temperature (typified by up to 1000° F. and above), high capacity (typified by up to 1,000,000 pounds of steam per hour and above) installations in which employment of a super heater such as here shown at S substantially increases the thermal efficiency of the generating unit, reduces the amount of work that must be done by the evaporative surfaces to produce the same power, and makes the steam transmittable without condensation as well as more efficiently useable by turbines and other consumption devices.

The representative boiler illustrated at B includes a lower water drum 10 plus upper steam and water drums 11 and 12 interconnected with the lower drum by banks of steam generating tubes 8, 13 and 14. The superheater S is located in the first pass of the boiler behind a front bank of boiler tubes 8; it receives the saturated steam generated in the boiler as discharged from rear upper drum 12 by way of conduits

15. Baffles 16 and 17 cause the gases from the furnace offtake 19 to pass serially over superheater S and the lower portion of tube banks 13 and 14 and thence back and forth around baffle 18 to the boiler offtake 21. Heat transfer from the furnace gases to the superheater is therefore mostly by convection; reception by the superheater of radiant heat from the furnace flame being blocked by shielding baffle 16 aided by front tube bank 8.

In the superheater by-pass arrangement shown, baffle 17 at the front of tube bank 13 is spaced below the upper steam and water drum 11 to form a by-pass entrance for some of the furnace 15 gases; a baffle 22 behind the tube bank 13 forms the rear wall of a by-pass channel 23; both baffles 17 and 22 continue in substantially parallel spaced relation across the lower portion of rear tube bank 14 to form a rearward continuation of the by-pass 23; and a damper 24 located at the lower end of baffles 18 and 22 controls the flow of gas from furnace offtake 19 through this by-pass 23.

Damper 24 may be opened and closed in any 25 suitable manner such as through linkage means including a pivoted support lever 25 for the damper, connecting link 26, guided rod 27, bell crank 28 and a vertical rod 29 which is caused to move up and down by means of a motor 30 driving the rod through reduction gearing 31 and an arm 32 which transmits positioning movement from the motor to the damper. An electric motor is here shown at 30; however an air motor, hydraulic cylinder or the like obviously 35 may be used in its place.

The illustrative furnace A of Figure 1 has two of its walls lined with water cooled tubes 34 as shown in Figures 1 and 2; the lower furnace portion has two opposing sides which slope inwardly to form a bottom hopper or throat 35; these sloping portions are faced with water cooled tubes 36 which continue upwardly to line the two remaining side walls of the furnace combustion chamber; and all of the wall lining tubes 34 and 36 are connected in water circulation with boiler B in the well known manner indicated.

The vertically tilttable burners 9

50. Serving to fire furnace A are a group of burners arranged in the lower portion thereof as shown at 9 (see Figures 1 and 2) above the hopper 35 and there suitably located such as at or near the furnace corners as indicated in Figure 2. When 55 so arranged the burners may satisfactorily project streams of fuel (in one or more forms as later indicated) and air into the furnace in directions tangential to the surface of an imaginary cylinder (again see Figure 2) located vertically within the furnace preferably at its center. Other burner arrangements are of course useable to fire the selected fuel (pulverized coal, oil, gas or the like).

Figure 3 shows a typical burner construction which permits either pulverized fuel or oil to be 60 burned in the furnace alone or both to be burned simultaneously (through obvious modification gas may be substituted for either of the named fuels or gas alone may be burned). This illustrative burner comprises air chambers 43 which are connected at their sides to an air duct for supplying air thereto (as indicated in Figure 2) from a suitable source typified by conduits 42 of Figure 1.

In Figure 3 six such air ducts 43 are disclosed, the first and sixth being used to supply air alone 65 to deflecting vanes or nozzle tips 45 for passage

therefrom into the furnace; the second and fifth each being provided with a pulverized fuel supply pipe 39 (leading from a fuel source not shown) and a conduit portion 40 extending through the duct for conveying the fuel from pipe 39 in a stream of air to a nozzle tip 41 and thence into the furnace where burning takes place; and the third and fourth air ducts 43 each being provided with an oil pipe (connected with an oil source) and a surrounding tube 46 extending through the duct to a nozzle tip 47 from which oil may be injected into the furnace for burning therein along with or instead of the pulverized fuel from nozzle tips 41.

Each of the represented fuel nozzle tips 41 may be rectangular in cross section; it is located between air deflecting vanes 44 lying symmetrically above and below the tip and connected thereto by end plates adjacent the air chamber walls 43 normal to the vanes; it is rotatable vertically on pins in horizontal bearings 48 in the end plates, the pins being mounted on the opposite walls of fuel conduit 40 adjacent the end of said conduit; and tip 41 and its supporting conduit 40 are formed at their juncture into a cylindrical socket joint.

The represented air nozzle tips 45 (associated with the first and sixth air ducts 43) likewise may be rectangular in cross section; each is provided with deflecting vanes shown as supported by end plates normal to the vanes; and each is rotatable vertically on pins in the horizontal support bearings 48 carried by end plates, the pins being mounted on the opposite walls of the conduit 43.

The represented oil nozzle tips 47 (associated with the third and fourth air ducts 43) are located within air deflecting vanes 44a which lie symmetrically around each tip and are connected to a tip-surrounding jacket by perforated inclined spacer plates 47a and end plates normal to the vanes. Each of these tips 47 comprises an oil nozzle and a surrounding jacket; and it is rotatable vertically on pins in horizontal supporting bearings 48 in the end plates, the pins being mounted on the opposite walls of the air conduit 43 adjacent the end of tube 46.

The just-described fuel, oil and air nozzle tips 41, 47 and 45 when turned upwardly or downwardly direct the issuing fuel and air streams accordingly; the distribution of air above and below the fuel streams issuing from each of the fuel nozzle tips 41 and 47 remaining symmetrical for any position of the nozzle tip. The effect of simultaneously adjusting the tilt of these burner nozzles is represented in Figures 4a-b-c and will be more fully considered later; obviously less than all of the fuel and air nozzles in each burner 9 may be so adjusted tiltwise, as the Patent 2,363,875 to Kreisinger et al. brings out.

For imparting tilting movement to each of the burner's represented nozzles 41, 45 and 47 use is made of a positioning rod 50 which is pivoted to an end-plate of the nozzle, offset with respect to bearing 48, and which has an exterior extension 51 connected with a bell-crank 52 that in turn receives nozzle adjusting movement from a vertical tilt rod 53. Upward movement of rod 53 tilts all of the burner nozzles (41-45-47) downwardly around their bearings 48 while downward movement of the rod swings all of the nozzles upwardly with respect to the horizontal.

Serving to impart such tilt adjusting movements to vertical rod 53 is a motor represented at 55 in Figure 3. An electric motor is here shown at 55; however, an air motor, hydraulic

cylinder or the like obviously may be used in its place. In the arrangement illustrated this burner-tilting motor 55 drives into reduction gearing 56 to rotate arm 57 and thereby move connecting link 58 joined with the lower end of tilt rod 53 as indicated. When arm 57 has the intermediate position represented all of the burner nozzles 41, 45 and 47 are aligned horizontally as Figures 1, 3 and 4b show; clockwise rotation of arm 57 thereupon imparts to each of the burner nozzles an upward tilt (the same for all) above the horizontal to some position such as that of Figure 4c; and counterclockwise rotation of arm 57 similarly imparts downward tilt to all of the burner nozzles (to some position such as that of Figure 4a).

Burner adjustment affords superior temperature control

- 20 In the absence of superheat control means a steam generator equipped with a convection-type superheater S and otherwise organized as shown in Figure 1 will upon changes in loading vary through objectionably wide limits the temperature of the superheated steam taken from outlet 60. Such convection-superheater apparatus has a rising steam temperature characteristic (as earlier indicated); and in going from light to heavy generator load a total rise in the named steam temperature of more than 100° F. is not uncommon for a unit such as illustrated (when without superheat control), while in going from heavy to light load a temperature drop of similar magnitude is experienced.
- 25 35 Steam-utilizing requirements of the present day make superheat temperature variation of this wide magnitude (100° F. or more) unpermissible, especially in the high-temperature high-pressure installations which supply turbines and other devices whose satisfactory operation (due to carefully chosen materials and limited clearances) requires that steam temperature variation be held within relatively close limits.
- 40 45 The demand for constant steam temperature at the superheater outlet 60, over a wide range in generator capacity, has thus presented a significant problem. It is one in which the temperature of the products of combustion leaving the furnace must be sufficiently high to effect the necessary heat transfer, yet avoid objectionable deposition of slag on the heat absorbing surfaces. For example, if the gas temperature is high enough at partial load to obtain full superheat, then at full load it may be too high to avoid slagging; moreover, a presence of deposits on furnace wall 34-36 and on the boiler surface 8 ahead of superheater S reduces the heat absorbing capacity of those surfaces and increases the gas temperature in the superheater zone.
- 50 55 60 These critical requirements led to development of the earlier-described adjustable burners 9 which can be tilted upward (see Figure 4c) or downward (see Figure 4a) to suit load conditions and thereby govern superheat temperature as taught by the Kreisinger et al. Patent 2,363,875 already mentioned. With this burner arrangement, applied as here illustrated to a furnace A having liberal volume, it is possible to control the furnace outlet temperature and thereby provide a positive means for regulating superheated steam temperature over a wide range in capacity.

In manipulating the burners, required temperature of the furnace outlet gas is obtained

by selective use of the available furnace volume, through positioning the zone of turbulent combustion (see Figures 4a-b-c), thereby varying the effectiveness of the furnace water wall areas; such manipulation, moreover, provides for variations in the total furnace heat absorption to compensate not only for changes in load but also for changes in the cleanliness factor of the water walls 34-36. Hence to maintain a given degree of superheat the burner nozzles may be directed upward as in Figure 4c, either during light load periods or when the walls are clean; and downward as in Figure 4a during heavy loads or when the walls are coated with dust or slag.

Prior to the present invention such tilting adjustment of the burner nozzles has been accomplished only in comparatively large increments and only under manual control, it having been considered that such burner nozzles did not lend themselves to automatic control. Thus, all past efforts to govern the superheat temperature through automatic means have been directed at supplemental by-pass damper means (such as shown at 24 in Figure 1) and have been confined to attempts to make same positionally responsive to departures of the named temperature from a desired value.

The improved temperature regulating facilities now to be disclosed remove the foregoing and other prior limitations and for the first time make possible a satisfactory and commercially acceptable control by automatic means of the tilting burners 9 alone, of the by-pass damper 24 alone, and of the burners and damper in uniquely related combinations.

The automatic burner tilting system of Figure 5

In Figure 5 there is represented an electrical control diagram organized to effect regulation of the superheated steam temperature through a unique automatic control of the furnace's tiltable burners 9. Responding to and at all times registering the temperature of the superheated steam in outlet 60 is a recording meter represented at 62 in each of Figures 1 and 5. This meter 62 may satisfactorily be of a type utilizing a thermocouple 63 in the stream of superheated steam passing through outlet 60 together with an electrical potentiometer circuit (not shown) and associated means which keep an instrument pointer 64 (of Figure 5) in a position along horizontal scale 65 accurately corresponding to and registering the superheated steam temperature in outlet 60.

Carried by pointer 64 is a contact 66 which moves horizontally therewith. As long as the superheated steam temperature stays at the desired value, contact 66 is disengaged from both of a pair of cooperating stationary contacts I and D. In the arrangement shown stationary contacts I and D are mounted on a slide 67 settable beneath horizontal scale 65 for the superheated steam temperature that it is desired to maintain constant. The illustrative setting shown by Figure 5 is at 750° F. This slide 67 also carries a second pair of stationary contacts Im and Dm which respectively become engaged by movable contact 66 when temperature errors registered by instrument 62 become relatively large.

The positioning motor 55 for the tilting burners 9 may satisfactorily be linked with all of the burner nozzles as shown in Figure 3. Each burner may be provided with a separate motor 55 and the motors all energized in parallel, or all four

burners may receive tilting movement from only a single motor through mechanical interconnections not here shown in detail but readily provable. In the description of Figure 5 which follows the latter arrangement will be assumed; and it will therefore be considered that the single motor represented at 55 in Figure 5 simultaneously effects the same tilting adjustment in all four of the furnace burners which are represented at 9 in Figures 1, 2 and 4.

This burner adjusting motor 55 may be of comparatively low capacity (fractional horsepower or higher as needed) suitable for energization from the control potential appearing between the two vertically-drawn supply conductors designated 72 and 76 in Figure 5. The named motor driving voltage may be either direct current (as the 110 volt control potential available in power stations) or alternating current (as 110 or 220 volts, either 25 or 60 cycles). To facilitate explanation it will be assumed that a 110 volt, 60 cycle per second alternating current voltage appears between supply conductors 72 and 76.

Current for operating burner motor 55 is at proper times fed thereto from the named source through a conductor 73. Connection (as later described) of that conductor with motor terminal R produces "forward" rotation which causes arm 57 to tilt all fuel and air nozzles of all burners 9 in the upward or flame-raising direction; similarly, connection of conductor 73 (again as later described) with terminal L causes motor 55 to rotate in the "reverse" direction and tilt (through arm 57) all of the burner nozzles in the downward or flame-lowering direction. In order to prevent motor 55 from moving arm 57 too far in either the upward tilting (clockwise in Figure 5) or the downward tilting (counterclockwise in Figure 5) direction, use is made of normally closed limit switches 74 and 75 respectively inserted in the "raise" and "lower" supply leads for motor 55 as per the diagram of Figure 5.

Translation of the earlier described temperature-change responses by master control instrument 62 into appropriate operations by the burner tilting motor 55 is effected through the medium of the two relays which the schematic diagram of Figure 5 illustrates at IR and DR. Each of these two relays may be of conventional type including the usual operating winding shown as a simple block directly over the relay's designation plus the contacts shown immediately underneath and identified with the winding by a vertical dotted line. In Figure 5 both relay windings are shown de-energized and all relay contacts are shown released or open.

The first or "increase" relay IR is activated by master control instrument 62 whenever the temperature of the superheated steam in outlet 60 (see Figure 1) drops below the desired value. In such event pointer 64 moves to the left along scale 65 and carries contact 66 into engagement with stationary contact I. This completes for relay IR an energizing circuit extending from the supply conductor 72 at the left of Figure 5 through conductor 78, engaged contacts 66 and I, conductor 79, the winding of relay IR, conductor 80 and a step timer 95 back to the supply conductor 76 at the right of Figure 5.

Thus activated relay IR moves its normally open contact 82 upwardly to the closed position and completes for burner tilting motor 55 a "forward" circuit extending from supply conductor 72 through conductor 73, relay contact 82, limit switch 74, terminal R of motor 55, the motor's

"forward" driving winding, and conductor 89 to the supply conductor 76. Thus energized motor 55 rotates forwardly causing arm 57 to pull member 53 downwardly and thereby tilt all fuel and air nozzles of all the furnace burners 9 in the upward direction. Such upward tilting lifts the flame body (see Figure 4) to a higher position in the water walled furnace A, shortens the vertical length of furnace wall tubes exposed to intense radiation before reaching offtake 19 and thus has the effect of flowing the gases across the superheater S at a higher temperature than before.

The second or "decrease" relay DR is activated by master control instrument 62 whenever the temperature of the superheated steam in outlet 60 (see Figure 1) rises above the desired value. In such event pointer 64 moves to the right along scale 65 and carries contact 66 into engagement with stationary contact D. This completes for relay DR an energizing circuit extending from the supply conductor 72 through conductor 78, engaged contacts 66 and D, conductor 84, the winding of relay DR, conductor 80, and step timer 95 to the supply conductor 76.

Thus activated relay DR moves its normally opened contact 86 upwardly to the closed position and completes for burner tilting motor 55 a "reverse" circuit extending from supply conductor 72 through conductor 78, relay contact 86, limit switch 75, terminal L of motor 55, the motor's "reverse" driving winding, and conductor 89 to supply conductor 76. Thus energized the motor rotates reversely causing arm 57 to push burner member 53 upwardly and thereby tilt the fuel and air nozzles of furnace burners 9 in the downward direction. Result is to lower the flame body (see Figure 4) in the water walled furnace A, expose the combustion gases to a greater length of the vertical wall tubes 34-36, and pass those gases from offtake 19 over the superheater S at a reduced temperature.

In my new automatic control organization the foregoing corrective adjustments in burner tilt proceed: (a) in a recurrently interrupted and hence relatively slow manner as long as the temperature error remains small; but (b) continuously for faster corrective response when the error becomes large. In the system of Figure 5 such step-type operation a is achieved by inserting the earlier-mentioned step timer 95 in the pick-up circuits for the "increase" and "decrease" temperature-adjusting relays IR and DR.

The step timer represented at 95 includes contacts 97-98 which are repeatedly closed and opened under the cyclic action of a cam 100 continuously rotated (at some relatively low speed such as about 1 R. P. M.) by a suitable synchronous or clock-type motor 99 energized over conductor 101 from the system's alternating current supply circuit 72-76. Motor 99 accordingly rotates timer cam 100 at the slow and uniform speed earlier assumed (1 R. P. M.); the two cam lobes represented then serve to move timer contact 98 up and down once each thirty seconds in regularly repeated cycles; and each upward movement engages contact 98 with companion contact 97 while each downward movement breaks that engagement.

For adjusting the ratio of "on" (engaged) to "off" (disengaged) periods in these recurring timer contact cycles, provision is made for moving the upper contact 97 either closer to or further away from the lower contact 98. As here shown, this provision takes the form of a second

cam 103 settable in different rotational positions by timer adjusting lever 104.

When lever 104 is turned counterclockwise to the extreme left each thirty second cycle of timer operation will include a five second "on" period during which contacts 97-98 are engaged and a twenty-five second "off" period during which contacts 97-98 are disengaged; turning lever 104 clockwise increases the length of the timer "on" periods and decreases the length of the timer "off" periods; and if lever 104 is set to the extreme clockwise position timer contacts 97-98 will remain continuously engaged throughout the full thirty second cycle. In this way there is provided a simple and effective adjustment in the relative lengths of timer "on" and "off" periods throughout a comparatively wide range.

With connections made as shown in Figure 5 the pick-up circuits for both relays IR and DR of Figure 4 have included therein the timer contacts 97-98 just described. Instead then of being continuously picked up by master control instrument 62 (over contacts 66 and I or 66 and D) each of the system relays IR and DR now is picked up only during each "on" period of timer contact engagement and is released during each intervening "off" period when timer contacts 97-98 are disengaged.

In the case of "increase" relay IR pick-up current supplied thereto over instrument contacts 66-I and conductor 80 passes through timer contacts 97-98. As long, therefore, as contacts 66-I of master instrument 62 remain engaged relay IR picks up only when timer contacts 97-98 are together and releases each time that those contacts are recurrently separated in the manner aforesaid. Result is that relay IR in controlling the burner tilting motor 55 then runs the motor not continuously but intermittently in step with the "on" periods of timer 95, the motor stopping during each timer "off" period.

Similarly, in the case of "decrease" relay DR, pick-up current supplied thereto over instrument contacts 66-D and conductor 80 also passes through timer contacts 97-98. As long, therefore, as contacts 66-D of master instrument 62 remain engaged, relay DR picks up only when timer contacts 97-98 are together and releases each time that timer contacts are recurrently separated in the manner aforesaid. Result is that relay DR in controlling the burner tilting motor 55 then runs the motor not continuously but intermittently in step with the "on" periods of timer 95, the motor stopping during each timer "off" period.

As will now be evident, the effect of step timer 95 is to slow down the speed with which each corrective adjustment of superheated steam temperature is effected by burner motor 55. This is because each "on" portion of the timer cycle is during corrective action accompanied by a running of the adjuster motor 55 and each intervening "off" (open contact interval) produces a waiting period between motor operations. Such waiting periods allow each corrective adjustment in burner tilt more fully to produce its ultimate change in superheated steam temperature before further adjustment is initiated; in this way any tendency for the regulating system to "hunt" by overshooting its corrective actions is effectively cared for.

The step timer 95 obviously may be arranged to provide operating cycles ("on" plus "off" periods) of either greater or lesser length than the thirty second duration earlier assumed (to

facilitate explanation). With the thirty second cycle length illustratively assumed, equal "on" and "off" periods (fifteen seconds each) may prove most suitable for certain steam generator installations; in other installations a shorter "on" and a longer "off" period may prove most satisfactory; and in still other steam generator installations a longer "on" and a shorter "off" period may result in the best operation. As earlier indicated, the optimum adjustment for each installation is readily effected through timer adjuster lever 104.

In my unique control organization of Figure 5 the step-type of corrective adjustment in the tilt of furnace burners 9 proceeds as just described only when the temperature error being corrected is relatively small, such as not more than about five degrees above or below the desired value (750° F. earlier assumed) of superheated steam temperature. Should the temperature error being corrected exceed the named limits then one or the other of a pair of auxiliary relays IF and DF is activated to take step timer 95 out of the pick-up circuits of "increase" and "decrease" relays IR and DR.

In the organization shown the first auxiliary relay IF is upon a steam temperature drop large enough to bring temperature-following contact 66 into engagement with a first large-error contact Im (of master instrument 62) energized over a circuit then completed by those contacts and represented as including conductors 78 and 83; likewise, the second auxiliary relay DF is upon a steam temperature rise large enough to bring master instrument contact 66 into engagement with a second large-error contact Dm energized over a similar circuit then completed by the contacts just named.

In either event the activated auxiliary relay IF or DF closes its normally-open contact 87 or 91 and thereby connects conductor 80 (common to the pick-up circuits of "increase" and "decrease" relays IR and DR) to supply conductor 76 directly over conductor 105 instead of through contacts 97-98 of step timer 95. Under this condition the corrective operation of burner tilting motor 55 instituted by relay IR or relay DR proceeds continuously rather than intermittently, and the large-temperature error thus is correctively reduced at a faster rate than otherwise would be the case.

How the automatic control system of Figure 5 operates

During operation of a steam generator such as shown in Figure 1 the firing rate of the furnace fuel is usually regulated (through conventional means forming no part of the present inventions and hence not here shown) to maintain a specified constant steam pressure (such as the 500 p. s. i. earlier assumed) at the superheater outlet 60; moreover, as changes in the demand for generated steam may tend to increase or decrease this pressure the fuel-firing rate is (by the means named) appropriately adjusted to bring the pressure back to desired value. At the 500 p. s. i. pressure assumed this means that the saturated steam as generated in boiler B and as fed into superheater S (by way of conduits 15) has a superheater-entering temperature which stays at or very close to 470° F. regardless of whether the generator loading is high, medium or low.

The manner in which the complete burner-tilt-

ing system of Figure 5 performs its intended functions will now be examined in the light of the above. Assume first that master control instrument 62 of Figure 5 is set to hold contact 66 between contacts I and D when the superheated steam temperature at outlet 60 (see Figure 1) has a selected value of 750° F.; next that the bypass damper 24 of Figure 1 continuously occupies the fully closed position there shown; and finally that all of the furnace burners 9 initially have their nozzles in a substantially horizontal fuel-and-air-flow position as indicated by Figure 4b.

The foregoing conditions accompany some intermediate value (such as say 50% of full rating) of steam generator loading. Due to the untilted positioning of burner nozzles (as represented in each of Figures 1, 3, 4b and 5) the fuel and air streams from all of the burners 9 (see Figure 2) have an initial horizontal direction into the furnace A and cause the main flame body to center itself at and slightly above the vertical location of the burners (see Figure 4b) in the water-walled combustion chamber. The water wall length (vertically) contacted by the flame gases prior to leaving furnace offtake 19 then is such that the gases flowing over superheater S (all of them since damper 24 is closed) have a temperature proper for imparting to the steam passing through the superheater just enough heat to maintain the superheated steam leaving outlet 60 at the desired total temperature of 750° F. (assumed 470° saturated temperature of the steam entering superheater S plus 280° F. added to that steam during passage through the superheater).

Assume now that the demand for generated steam falls off thus decreasing the steam generator loading to some lower value (such as 25% rated) at which a considerably lesser quantity of fuel is supplied to burners 9 for combustion in furnace A. The furnace flame body now burns with diminished intensity and the temperature of the furnace gases is correspondingly lowered. The resultant stepped down transfer of heat to superheater S cuts down the total steam temperature in outlet 60 to some value less than the 750° F. desired.

This temperature lowering is at once registered by master control instrument 62 which in moving indicator 64 to the left engages contact 66 with contact I to initiate an appropriate "increase" adjustment in the superheated steam temperature. In responding (as earlier explained) relay IR closes its contact 82 thereby completing for burner tilting motor 55 the "forward" circuit earlier traced to cause an upward tilting of all fuel and air nozzles of all of the furnace burners 9 as previously described.

Such upward tilting inclines the fuel streams above the horizontal (see Figure 4c) and thereby lifts the flame body to a higher position in water walled furnace A; such raising shortens the vertical length of furnace wall tubes exposed to intense radiation from the combustion gases before same reach offtake 19 and thus has the effect of flowing the gases across superheater S at a higher temperature than before; and the resultant stepping up of heat transfer to the superheater raises the temperature of superheated steam leaving outlet 60.

In responding to this corrective increase master instrument 62 moves pointer 64 to the right. When this movement reaches the desired 750° F., contact 66 separates from contact I, relay IR becomes de-energized and opens contact 82, and

motor 55 discontinues its tilt raising adjustment of the fuel and air nozzles of furnace burners 9. This completes the corrective elevation of superheated steam temperature occasioned by the earlier assumed drop in steam generator output.

Should the steam generator output be decreased still further the temperature of the superheated steam may again decrease and cause instrument 62 again to bring contact 66 into engagement with contact I. This once more picks up relay IR and causes motor 55 to still further increase the upward tilt of the fuel and air nozzles in burners 9. Obviously if the steam generator loading goes too low a point will be reached when this upward tilting action reaches the limit of nozzle travel (a condition represented in Figure 4c) in the flame-raising direction. When this happens, burner adjusting member 53 occupies its limiting position of downward travel wherein actuator 90 opens limit switch 74 and thereby breaks the forward (tilt raising) driving circuit for burner motor 55.

Assume next that the steam generator loading starts to build up. More fuel is then supplied to burners 9 and the temperature of the furnace gases passing over superheater S is correspondingly raised. More heat is now transferred to the steam passing through the superheater, and this is reflected by a raising of the superheated steam temperature in outlet 60. Master control instrument 62 registers this, brings contact 66 into engagement with contact D and picks up (as earlier explained) "decrease" relay DR to effect closure of its contact 86. That closure completes for burner tilting motor 55 the "reverse" circuit earlier traced to cause a downward tilting of all fuel and air nozzles of all of the furnace burners 9 as previously described.

Result of this downward tilting is to bring the flame body back to a lower location in water walled furnace A and to require that the combustion gases be exposed to a greater length of the vertical wall tubes 34 and 36 (see Figures 1 and 2) before reaching furnace oftake 19. In consequence the gases flowing over superheater S now have a lower temperature than before, and the transfer of heat therefrom to the steam passing through the superheater is correspondingly cut down. This in turn reduces the temperature of the superheated steam in outlet 60 and causes master control instrument 62 to move its indicator 64 to the left.

When the superheated steam temperature has thus been corrected back to the desired value of 750° F., contact 66 disengages from contact D, relay DR is deenergized, the accompanying opening of contact 86 disconnects motor 55 from its energizing source, and tilt lowering adjustment in the fuel and air nozzles of furnace burners 9 is thereupon discontinued.

Further increases in steam generator loading are accompanied by further corresponding increases in fuel supply to and heat liberation within furnace A. Each of these increases produces a corresponding rise in superheated steam temperature (in outlet 60) immediately followed by an appropriate further lowering of nozzle tilt in the furnace burners 9. Each of these further corrective actions proceeds as just explained above. In this manner the burner nozzles are brought back to the horizontal position represented in Figures 1, 3, 4b and 5 when the generator loading has risen to some intermediate value assumed to be 50% full rated generator load (this assumption is not

necessarily accurate but is made to facilitate description).

Still further rises in steam generator output are accompanied by further increases in furnace fuel supply, and through the automatic control system of Figure 5 they effect additional downward tilting of the burner nozzles to fuel-stream-directing positions below the horizontal. As the generator loading is thus progressively increased, a point is eventually reached at which burner motor 55 has brought the fuel and air nozzles to the extreme downward limit (a condition represented in Figure 4a) in their range of tilting travel. When this happens, the limiting point of superheat control in this temperature-decreasing direction will have been reached by burners 9 and limit switch 75 then will be opened by actuator 90. To facilitate description it will be assumed that this limit switch opening occurs when the generator loading has risen to 100% of full rated value.

Upon subsequent dropping of steam generator load below this assumed 100% full rated value, the accompanying decrease in superheat temperature is registered by instrument 62 to pick up "increase" relay IR, run (over contact 82) burner motor 55 in the forward direction, and thereby adjust the fuel and air nozzles of burners 9 (from the extreme downward position of Figure 4a) in the tilt-raising direction. Such adjustment brings the burner flame body to a higher point in furnace A and restores the superheat temperature back to desired value.

Continued falling off in the steam generator loading acts in this manner progressively to raise the tilt of the burner's fuel and air nozzles; in this way those nozzles are brought back to the substantially horizontal position (shown by Figures 1, 3, 4b and 5) when the steam generator loading has returned to the intermediate value (as of the order of 50% rated) first assumed at the beginning of this operation description for the Figure 5 control system.

In all of the Figure 5 adjustments in burner tilt thus far described the corrective action proceeds: (a) intermittently when the temperature error being corrected is small, due to auxiliary relays IF and DF then being de-energized and step timer 95 then being included in the pick-up circuits of main corrective relays IR and DR; and (b) continuously when the temperature error being corrected is large enough to engage instrument element 66 with contact Im or Dm and pick-up relay IF or DF to render step timer 95 ineffective as earlier explained.

An initially large temperature error therefore produces a continuous corrective action which adjusts the temperature back toward normal at the fastest possible rate; this continuous or fast adjustment continues until the error has been reduced to only several degrees at which time instrument element 66 leaves contact Im or Dm to reinsert step timer 95 back into the main relay IR-DR pick-up circuit; and from then on further and final correction of the temperature error proceeds in the intermittent manner established by step timer 95 and already explained as minimizing hunting and preventing the corrective adjustment from proceeding beyond the point necessary.

Certain features of the foregoing control facilities of Fig. 5 form the subject matter of divisional application Serial 232,488 filed June 20, 1951 under title of "Superheat Control by Automatic Tilting Burner Means."

The composite burner-damper control system of Figure 6

In Figure 6 there is represented an electrical control diagram wherein the unique form of automatic control just explained for the furnace's tiltable burners 9 is at proper times extended to the superheater's by-pass damper represented at 24 in Figure 1. In this composite organization of Figure 6 primary control of the superheated steam temperature is assigned to the named burners and secondary control thereof to the named damper.

All Figure 5 elements for controlling the tilting burners 9 have been reproduced in Figure 6 and hence need not again be described. Supplementing these are the by-pass damper 24, its positioning motor 30, driving circuits for that motor including contacts 81 and 85 of relays IR and DR, a burner-actuated contact 88 in those driving circuits, and a damper-actuated contact 71 in the circuits which drive the burner motor 55.

The positioning motor 30 for by-pass damper 24 may satisfactorily be of comparatively low capacity (fractional horsepower or higher as needed) suitable for energization from the control potential appearing between the two vertically-drawn supply conductors 72 and 76 of Figure 6. There current for operating the damper motor 30 is at proper times fed thereto through a conductor 68.

Connection (as later described) of that conductor with motor terminal C produces "forward" rotation by motor 30 which causes arm 32 to move damper 24 toward the closed position represented; similarly, connection of conductor 68 (again as later described) with terminal 0 causes motor 30 to rotate in the "reverse" direction and thereby move (through arm 32) damper 24 in the opening direction. In order to prevent motor 30 from moving arm 32 too far in either the damper closing (clockwise in Figure 6) or the damper opening (counterclockwise in Figure 6) direction use is made of normally closed limit switches 69 and 70 respectively inserted in the "close" and in the "open" supply leads of motor 30 as per the Figure 6 diagram.

In the fully closed damper position represented limit switch 69 has been opened, and contact 71 also actuated by damper arm 32 has been closed. The latter contact 71 (in the driving circuits for burner motor 55) is closed only when damper 24 is fully closed; at all other times it remains open. Obviously, however, the system may be set up to effect closure of this contact 71 at given positions of damper 24 other than the fully closed one here selected for purposes of illustration.

In the intermediate burner-tilt position (corresponding to Figure 4b) represented in Figure 6, the burner-actuated contact 88 (in the driving circuits for damper motor 30) is opened; it closes only when the burners occupy the position of maximum downward tilt as represented in Figure 4a. Obviously, however, the system may be set up to effect closure of this contact 88 at given positions of burner tilt other than the maximum downward one here selected for purposes of illustration.

How primary burner control system of Figure 6 operates

In considering operation of the composite burner-damper control system of Figure 6, ini-

5 tally assume (as was done in explaining Figure 5) that master control instrument 62 is set to hold element 66 between contacts I and D when the superheated steam temperature at outlet 60 (see Figure 1) has a selected value of 750° F.; that the by-pass damper 24 occupies the fully closed position shown wherein contact 71 assigns burner tilting motor 55 to control by relays IR and DR; and that all of the furnace burners 9 have their nozzles in a substantially horizontal fuel and air flow position (as in Figure 4b) wherein contact 88 actuated by burner tilting member 53 is open to keep damper motor 30 continuously de-energized and hence unresponsive to control by relays IR and DR.

20 The foregoing conditions accompany some intermediate value (such as say 50% of full rating) of steam generator loading. For all lower values of generator loading the necessary regulation of steam temperature at superheater outlet 60 is accomplished through tilting burners 9 automatically adjusted as in the system of Figure 5 earlier described; and for higher values of generator loading which do not reach or exceed some predeterminedly high value, such as 100% rating for the unit, a similar statement can be made.

25 This is because contact 88 actuated by burner tilt rod 53 closes only when the furnace burners 9 have been adjusted to their Figure 4a position of maximum downward tilt corresponding to the assumed 100% rated generator loading. For all lesser load values this contact 88 remains open and prevents damper motor 30 from receiving driving current upon closure either of relay IR's contact 81 or of relay DR's contact 85. Damper 24 thus stays in the fully closed position represented wherein contact 71 maintains the "forward" and "reverse" driving circuits for burner motor 55 set up for selective completion upon respective closure of IR relay contact 82 and DR relay contact 86.

30 Hence within the generator load range cared for by tilting burners 9 the response by tilt-adjusting motor 55 to relays IR and DR is the same as in the earlier-described system of Figure 5. But, as the generator loading is progressively increased, a point is ultimately reached at which motor 55 brings the fuel and air nozzles to their limiting position of downward tilt as represented in Figure 4a.

35 When this happens, actuator 90 opens limit switch 75 while burner tilting member 53 effects a closure of contact 88 and thereby connects damper motor conductor 68 with the supply conductor 76. Such connection conditions damper positioning motor 30 for response to pick ups on the part of relays IR and DR. As earlier indicated, the flame body within furnace A is by burners 9 (whose nozzles are tilted as far downwardly as possible) now retained in the extreme lower portion of water walled furnace A (see Figure 4a).

40 As the loading on the steam generator is additionally raised, the resultant increase of fuel supply to and heat liberation in this flame body raises the temperature of the combustion gases leaving the furnace exit 19 and passing over the superheater S. The resultant increase in heat transfer thereto again increases the temperature 45 of the superheated steam in outlet 60 and causes master control instrument 62 once more to move indicator 64 to the right and bring contact 66 into engagement with "decrease" contact D.

45 This picks up relay DR and closes both contacts 75 85 and 86 thereof. Limit switch 75 now being

open, burner motor 55 does not respond to contact 86 and the fuel and air nozzles of all furnace burners 9 accordingly remain in their limiting position of downward tilt wherein burner actuated contact 88 is closed as aforesaid.

Under these conditions the closure of relay DR's contact 85 completes for damper motor 30 a "reverse" energizing circuit which extends from the supply conductor 72 through conductor 92, the reverse driving winding of motor 30 ending in terminal 0, closed limit switch 70, relay contact 85, conductor 68 and closed burner contact 88 to the supply conductor 76.

Thus energized motor 30 rotates reversely causing arm 32 (rotating counterclockwise in Figure 6) to open by-pass damper 24. From Figure 1 it can be seen that such opening allows a portion of the combustion gases from furnace offtake 19 to be diverted through passage 23 (between baffles 17 and 22) without passing over the main body of superheater S. In consequence of the reduction in furnace gas volume which contacts the superheater, the heat absorbed thereby is reduced and the temperature of the superheated steam in generator outlet 60 is correspondingly lowered.

Such lowering is registered by master control instrument 62 which in moving indicator 64 to the left disengages contact 66 from contact D upon return of the registered temperature to the desired value (750° F.). The named disengagement releases relay DR, opens contacts 85 and 86, breaks (at contact 85) the driving circuit for motor 30 and thereby stops the earlier initiated opening of by-pass damper 24.

Still further increases in steam generator loading cause further corrective openings of the by-pass damper through the same sequence of actions as described above. In this manner a point is eventually reached at which motor 30 has brought damper 24 to its extreme limit of travel in the opening direction. When this happens, limit switch 70 is opened by actuator 93 and motor 30 will thereafter be unresponsive to pick ups by "decrease" relay DR. To facilitate explanation it will be assumed that this arrival of by-pass damper 24 at its extreme position in the opening direction occurs when the steam generator loading has been increased to 125% of full rated value.

When now the steam generator loading starts to decrease, the accompanying reduction in fuel supply to and heat liberation in furnace A causes the combustion gases leaving furnace offtake 19 to have a correspondingly lower temperature. The portion of those gases which (under the fully opened condition of by-pass damper 24) flow over the main body of superheater S now transfer less heat thereto so that the superheated steam temperature in outlet 60 correspondingly drops.

In registering this drop master control instrument 62 moves indicator 64 to the left, engages contact 66 with "increase" contact I and thereby picks up relay IR. The accompanying closure of that relay's contact 82 has no effect on burner motor 55 for the reason that damper actuated contact 71 (in the circuit of that motor) was opened when by-pass damper 24 moved out of its fully closed position (shown in Figure 6). The furnace burners 9 therefore continue to hold their fuel and air nozzles in the position of maximum downward tilt (Figure 4a).

In closing its contact 81 "increase" relay IR completes for damper motor 30 a "forward" energizing circuit which extends from supply con-

ductor 72 through conductor 92, the forward driving winding of motor 30 ending in terminal C, closed limit switch 69, closed contact 81 of relay IR, conductor 68 and closed burner contact 88 to the supply conductor 76. Thus energized motor 30 rotates forwardly causing arm 32 (moving clockwise in Figure 4) to move by-pass damper 24 in the closing direction. Such movement cuts down the flow of by-pass gas through channel 23 and causes a greater portion of the total furnace gas to flow over the main body of superheater S.

The resultant increase in heat transfer to the superheater is reflected by a rise in the temperature of the superheated steam leaving generator offtake 60. In registering this rise master control instrument 62 moves indicator 64 to the right, disengages contact 66 from contact I, releases relay IR and breaks (at contact 81) the driving circuit for damper motor 30. This discontinues the damper closing movement earlier initiated and stops by-pass damper in the position now proper for holding the superheated steam temperature at the desired value.

Further reductions in steam generator loading are accompanied by corresponding drops in the temperature of the superheated steam leaving generator offtake 60; each such drop causes instrument 62 again to pick up "increase" relay IR and run motor 30 still further in the damper closing direction. In this manner a continuing falling off in the generator load eventually moves by-pass damper 24 to the fully closed position shown by Figure 6 wherein limit switch 69 is opened by actuator 93 to render motor 30 unresponsive to further driving in the forward or damper closing direction through contact 81 of "increase" relay IR. To facilitate explanation it will again be assumed that this point corresponds to a steam generator loading of 100% full rated value.

With the by-pass damper 24 thus fully closed, contact 71 actuated by damper member 29 again occupies the closed position shown by Figure 6 wherein the driving circuits for burner motor 55 are again set up for response to pick ups by relays IR and DR. Meanwhile, all of the fuel and air nozzles of furnace burners 9 continue to stay in their position of extreme downward tilt (Figure 4a); burner limit switch 75 continues to be held opened by actuator 90; while contact 88 actuated by tilting member 53 continues closed as aforesaid.

Under these circumstances, any rise in steam generator loading will be cared for by by-pass damper 24 and motor 30 as regards adjustment of superheated steam temperature; but any drop in steam generator loading will now be cared for by furnace burners 9 and tilting motor 55 with regard to corrective adjustment in superheated steam temperature.

Thus when the steam generator loading drops below the assumed 100% full rated value, the accompanying decrease in superheat temperature as registered by instrument 62 picks up "increase" relay IR and runs (over contact 82) burner motor 55 in the forward direction to adjust the fuel and air nozzles of burners 9 in the tilt raising direction. Such adjustment brings the burner flame body to a higher point in furnace A and restores the superheat temperature back to desired value.

Continued falling off in the steam generator loading acts in this manner progressively to raise the tilt of the burner's fuel and air noz-

zles; in this way those nozzles are brought back to the substantially horizontal position of Figure 4b when the steam generator loading has returned to the intermediate value (as of the order of 50% rated) first assumed at the beginning of this operation description for the Figure 6 control system.

With this system it will accordingly be seen that when the steam generator loading is in the range below some predetermined value (here illustratively assumed as 100% rated) all corrective adjustments in superheated steam temperature are effected through the medium of tilting burners 9; that when the generator loading lies in the range above that predetermined value (100% rated assumed as aforesaid) all required control of the superheated steam temperature is provided through the medium of by-pass damper 24; and that the total range of generator load variation accompanied by effective superheat temperature control thus has been increased to the sum of the two load ranges individually cared for by the two controlling instrumentalities (tiltable burners 9 and by-pass damper 24). In the illustrative example given, the burners 9 thus take care of generator loadings from an extremely low value up to an assumed 100% full rated value while the by-pass damper 24 accomplishes all necessary superheat temperature control for generator loadings of from 100% to an assumed 125% rated value.

In all of the Figure 6 adjustments in damper positioning and in burner tilt which have been described the corrective action proceeds: (a) intermittently when the temperature error being corrected is small, due to auxiliary relays IF and DF then being de-energized and step timer 95 then being included in the pick-up circuits of master relays IR and DR; and (b) continuously when the temperature error being corrected is large enough to engage element 66 with contact Im or Dm and pick-up relay IF or DF to render step timer 95 ineffective as earlier explained.

The by-pass damper 24, as well as the tilting burners 9, therefore responds to an initially large temperature error to produce a continuous corrective action which adjusts the temperature back towards normal at the fastest permissible rate; this continuous or fast adjustment (by the damper or by the burners, whichever is responding) continues until the error has been reduced to only several degrees, at which time instrument element 66 leaves contact Im or Dm to reinsert step timer 95 back into the main relay IR-DR pick-up circuit; and from then on further and final correction of the temperature error proceeds in the intermittent manner established by step timer 95, which is effective to prevent corrective action overshoot (as earlier indicated).

The primary damper control system of Figure 7

In the Figure 6 control system just described the tiltable burners 9 effect superheat temperature regulation over a major portion of the steam generator loading range (illustratively assumed to be everything below 100% rating) while the by-pass damper 24 then comes into effect only after full capability of the burners to adjust superheat temperature has been reached. In the Figure 6 system the furnace burners can therefore be regarded as accomplishing primary control of the superheat temperature while the by-pass damper 24 (effective only in the highest range of steam generator loading) can be re-

garded as a secondary control of superheat temperature which serves to extend the total range of generator load variation effectively provided for.

5 In the modified system of Figure 7 a somewhat different arrangement is used in that bypass damper 24 may be regarded as providing the primary control of superheat temperature while the furnace burners 9 supplement same 10 only when needed to shift the damper range so as to embrace the particular value of steam generator loading being dealt with.

Comparison of Figure 7 with Figure 6 will reveal that the Figure 7 circuit organization exactly duplicates the Figure 6 organization except for the following differences: (a) burner actuated contact 88 of Figure 6 has been eliminated from Figure 7; (b) damper actuated contact 71 of Figure 6 has in Figure 7 been replaced by a 20 pair of contacts 71a-71b; and (c) the reverse or tilt lowering driving circuit for burner motor 55 (which includes contact 86 of relay DR) is in Figure 7 carried separately through damper contact 71b.

25 These changes cause the Figure 7 system to operate in the modified manner which will now be explained. Assume that the steam generator loading has some intermediate value such as 50% rated. Under this condition the by-pass damper 24 will be partially opened as indicated in Figure 7 while the fuel and air nozzles of furnace 30 9 will also have some intermediate position in their tilt range such as the horizontal one of Figure 4b.

35 Assume next that there occurs a rise in steam generator loading which calls for greater fuel supply to and heat release in the furnace, with consequent initial elevation in the temperature of the superheated steam leaving generator outlet 60. Master control instrument 62 registers this initial rise to pick-up relay DR over contact 66-D and thereby close relay contacts 85 and 86. But, the closure of contact 86 cannot operate burner motor 55 for the reason that the reverse 40 driving circuit therefor is now broken at damper contact 71b.

45 However, the closure of relay DR's contact 85 completes the "reverse" driving circuit for damper motor 30 (conductor 68 now being directly connected with the supply conductor 76). Motor 30 accordingly moves by-pass damper 24 in the opening direction to divert more of the furnace gases from contact with superheater S and thereby bring the superheat steam temperature back down to the desired value.

50 If the increment of steam generator load increase was large enough to cause motor 30 thus to fully open damper 24, limit switch 70 will be opened by actuator 93 at the same time that damper contact 71b closes and connects relay DR's contact 86 with the supply conductor 72. Should contacts 66-D of master instrument 62 then still be engaged, closed contact 86 of relay DR now becomes effective to run burner motor 55 reversely and thereby tilt the fuel and air nozzles of furnace burners 9 in the downward direction.

55 This downward tilting action by motor 55 continues until the superheated steam temperature as measured by master instrument 62 returns to the desired value at which instrument contact 66 disengages from contact D to de-energize relay DR and thereby discontinue burner lowering operation of motor 55. Further increases in the generator loading repeat the just described super-

21

heat temperature adjusting action on the part of burner motor 55.

If now the steam generator loading falls with attendant decrease in furnace fuel supply and lowering of the superheated steam temperature, master instrument 62 engages contact 66 with contact I to pick up "increase" relay IR. The attendant closure of contact 82 cannot operate burner motor 55 for the reason that the forward driving circuit therefor is now broken at damper contact 11a.

But, the attendant closure of relay IR contact 81 drives damper motor 30 forwardly and thereby moves by-pass damper 24 in the closing direction. If the increment of generator loading decrease is within the temperature correcting range of by-pass damper 24 master instrument contact 66 disengages from contact I before the damper has been fully closed and stops the damper in that new position.

However, if full closure of damper 24 has not brought the superheated steam temperature back to the desired value, relay IR will continue to hold contacts 81 and 82 closed. Contact 81 has no effect on damper motor 30 for the reason that limit switch 69 has now been opened by actuator 93. That opening, moreover, was accompanied by a closure of damper contact 71a to connect relay contact 82 (in the burner motor circuit) with the supply conductor 72.

In consequence of this 71a closure relay IR's contact 82 now drives damper motor 55 in the forward direction to move the fuel and air nozzles of furnace burners 9 in the tilt raising direction. Such movement continues until the initially lowered superheated steam temperature is restored to the desired value at which contact 66 de-energizes relay IR and stops motor 55.

Should the steam generator loading now be increased, the resultant rise in superheated steam temperature as registered by instrument 62 picks up relay DR. The attendant closure of relay contact 86 has no effect on burner motor for the reason that the reverse driving circuit for this motor is now broken at the damper contact 11 (which closes only when by-pass damper 24 is fully opened). But the attendant closure of relay DR's contact 85 drives damper motor 30 in the reverse direction and starts to move by-pass damper 24 in the opening direction (from the previous fully closed position).

This opening of damper 24 continues either until the superheated steam temperature is brought back to normal (to release relay DR and stop motor 30) or until damper 24 becomes fully opened to break the motor driving circuit at limit switch 70 and at the same time to close contact 11b in the reverse driving circuit for burner motor 55. In the former event the corrective action is completed; in the latter burner motor 55 comes into action to move the fuel and air nozzles of furnace burners 9 in the tilt lowering direction as may be required to restore the superheated steam temperature back to normal.

In all of the Figure 7 adjustments in damper position and in burner tilt which have been described the corrective action: (a) proceeds intermittently when the temperature error being corrected is small, due to auxiliary relays IF and DF then being de-energized and step timer 95 then being included in the pick-up circuits of master control relays IR and DR; and (b) proceeds continuously when the temperature error is large enough to engage instrument element 66 with contact Im and Dm and pick-up

22

relay IF or DF to render step timer 95 ineffective as earlier explained.

An initially large temperature error therefore produces a continuous corrective action (as in the earlier-described systems of Figures 5 and 6); this continuous or fast adjustment continues until the error has been reduced to only several degrees; and from then on further and final correction of the temperature error proceeds in the intermittent manner established by step timer 95 to prevent each corrective action from proceeding beyond the point necessary.

It will, accordingly, be seen that in the Figure 7 circuit organization primary control of the superheated steam temperature is effected through the medium of by-pass damper 24 while the tiltable furnace burners 9 come into action only when the magnitude of a given change in steam generator loading exceeds the temperature corrective range of the by-pass damper. However, as in the system of Figure 6 there is provided an effective control of superheat temperature throughout a total range of steam generator loading variation, which is the sum of the individual ranges of the by-pass damper 24 and of the tiltable furnace burners 9 (each of these two instrumentalities being effective in a given installation to hold the superheated steam temperature constant through and only through a certain range of generator ratings).

Summary

From the foregoing, it will accordingly be seen that I have provided improved means for obtaining the desired steam temperature from the convection superheater of a conventional water-walled steam generator by automatically regulating (through tilting burners) the heat absorption within the furnace as the major basis of control and also (when desired) the by-passing of furnace gases around the superheater as a supplemental basis of control; that I have provided automatic control means responsive to the superheated steam temperature and uniquely effective to adjust in advantageous and commercially satisfactory ways either the tilting burners or the by-pass damper or both; that I have coordinated the heat absorption or tilting burner means with the gas by-pass or damper means in such a way that the temperature control ranges of the two are additive; and that I have provided automatic control systems responsive to superheated steam temperature which are effective to adjust the co-ordinated tilting burner and by-pass means in predetermined advantageous ways.

In actual practice the herein-disclosed unique automatic control of the tiltable burners 9 has shown advantages which are both significant and unexpected; all operating experience thus far acquired having demonstrated that individual automatic control of tilting burners is far superior to and hence much to be preferred over individual automatic control of a by-pass damper.

For example, in using tiltable burners as the regulator of superheated steam temperature the furnace exit gases are effectively prevented from getting objectionably hot (high loads being accompanied by low flame positionings as shown in Figure 4a); whereas if only a by-pass damper (such as 24 in Figure 1) is depended upon to accomplish superheat regulation the temperature of the furnace exit gases cannot be so held down at high generator loadings and objectionable slag deposits on the heating tube surfaces then are likely to occur. In addition superior efficiency in heat transfer to the boiler water is achieved.

with the by-pass damper 24 held fully closed and all superheat control provided by the tilting burners for then all furnace gases traveling through boiler B follow the circuitous path which enables better heat transfer than does a bypassing flow through channel 23.

Moreover, the here-disclosed tilting burner method of automatic superheat regulation involves a sweeping of the flame body up and down in the furnace with changing generator load as diagramed by Figures 4a-b-c. Operating experience demonstrates that such recurrent change in vertical flame location gives a totally unexpected advantage of keeping the furnace wall tubes 34-36 relatively clean and free from the slag deposits which build up when the flame is held in a single vertical location, as in conventional furnace organizations of the prior art. In consequence coals and other fuels of a wider grade can be successfully burned in a furnace equipped with automatically tilted burners 9 than in a furnace wherein the burners are not so controlled incident to superheat temperature regulation.

The foregoing special advantages of automatic burner tilt control therefore have a wide practical significance and vastly extend the performance capabilities of steam generators such as therein considered. My inventive improvements are therefore extensive in their application and hence are not to be restricted to the specific form here disclosed by way of illustration.

What I claim is:

1. In a steam generator, a generally vertical furnace having a gas outlet at one end and walls lined with water cooled tubes, burners in the vicinity of the other furnace end for introducing into the furnace at a point remote from said gas outlet streams of fuel and air which create a mass of burning gas within said tube lined walls, a superheater carrying steam from the generator and receiving heat from the furnace gases which leave said outlet, a passage through which a portion of said furnace gases may bypass around said superheater and thereby cut down heat transfer thereto, a damper for adjusting the flow of said by-pass gases, means for tilting said burners whereby to alter the angle to the horizontal of the direction of said fuel and air streams so as to bring the vertical location within the tube lined walls of said mass of burning gas closer to or more remote from the furnace's said gas outlet, a motor for imparting tilt adjusting movement to said burners through said means, another motor for imparting position adjusting movement to said by-pass damper, an instrument for registering the temperature of the steam leaving said superheater, forward and reverse driving means for said burner motor respectively activatable by said instrument when said leaving-steam temperature falls below and rises above a desired value and then effective respectively to adjust said burners in direction bringing said burning gas mass closer to the furnace gas outlet and in direction bringing said mass further away from said outlet, forward and reverse driving means for said damper motor respectively activatable by said instrument when said steam temperature falls below and rises above said desired value and then effective respectively to adjust said damper in the by-pass gas decreasing and in the by-pass gas increasing direction, and control transfer means responsive to changes in steam generator loading and functioning to cause said instrument to govern the aforesaid driving means for one of the aforesaid two motors when that loading is within a given range and to govern the aforesaid driving means for the other of those motors when the generator loading is outside of said given range.

2. In a steam generator, the said damper motor driving means at other times.

2. In a steam generator, a generally vertical furnace having a gas outlet at one end and walls lined with water cooled tubes, burners in the vicinity of the other furnace end for introducing into the furnace at a point remote from said gas outlet streams of fuel and air which create a mass of burning gas within said tube lined walls, a superheater carrying steam from the generator and receiving heat from the furnace gases which leave said outlet, a passage through which a portion of said furnace gases may bypass around said superheater and thereby cut down heat transfer thereto, a damper for adjusting the flow of said by-pass gases, means for tilting said burners whereby to alter the angle to the horizontal of the direction of said fuel and air streams so to bring the vertical location within the tube lined walls of said mass of burning gas closer to or more remote from the furnace's said gas outlet, a motor for imparting tilt adjusting movement to said burners through said means, another motor for imparting position adjusting movement to said by-pass damper, an instrument for registering the temperature of the steam leaving said superheater, forward and reverse driving means for said burner motor respectively activatable by said instrument when said leaving-steam temperature falls below and rises above a desired value and then effective respectively to adjust said burners in direction bringing said burning gas mass closer to the furnace gas outlet and in direction bringing said mass further away from said outlet, forward and reverse driving means for said damper motor respectively activatable by said instrument when said steam temperature falls below and rises above said desired value and then effective respectively to adjust said damper in the by-pass gas decreasing and in the by-pass gas increasing direction, and control transfer means responsive to changes in steam generator loading and functioning to cause said instrument to govern the aforesaid driving means for one of the aforesaid two motors when that loading is within a given range and to govern the aforesaid driving means for the other of those motors when the generator loading is outside of said given range.

3. In a steam generator, a generally vertical furnace having a gas outlet at one end and walls lined with water cooled tubes, burners in the vicinity of the other furnace end for introducing into the furnace at a point remote from said gas outlet streams of fuel and air which create a mass of burning gas within said tube lined walls, a superheater carrying the generated steam and receiving heat from the furnace gases which leave said outlet, a passage through which a portion of said furnace gases may bypass around said superheater and thereby cut down heat transfer thereto, a damper for adjusting the flow of said by-pass gases, means for tilting said burners whereby to alter the angle to the horizontal of the direction of said fuel and air streams so as to bring the vertical location within the tube lined walls of said mass of burning gas closer to or more remote from the furnace's said gas outlet, a motor for imparting tilt adjusting movement to said burners through said means, another motor for imparting position adjusting movement to said by-pass damper, an instrument for registering the temperature of the steam leaving said superheater, forward and reverse driving means for said burner motor respectively activatable by said instrument when said leaving-steam temperature falls below and rises above a desired value and then effective respectively to adjust said damper in the by-pass gas decreasing and in the by-pass gas increasing direction, and control transfer means for causing said instrument to govern as aforesaid the said burner motor driving means at times and

said instrument when said leaving-steam temperature falls below and rises above a desired value and then effective respectively to adjust said burners in direction bringing said burning gas mass closer to the furnace outlet and in direction bringing said mass further away from said outlet, forward and reverse driving means for said damper motor respectively activatable by said instrument when said steam temperature falls below and rises above said desired value and then effective respectively to adjust said damper in the by-pass gas increasing and in the by-pass gas decreasing direction, means for causing said instrument to govern as aforesaid the forward and reverse driving means of said burner motor at times and the forward and reverse driving means of said damper motor at other times, a step timer effective to cause the aforesaid corrective operations of said burner tilting and damper positioning motors to proceed intermittently and hence relatively slowly as long as only a small difference exists between said desired value of superheated steam temperature and the actual value thereof as registered by said instrument, and means effective when said superheated steam temperature as registered by the instrument departs widely from said desired value for causing the accompanying corrective operation by the burner tilting motor or the damper positioning motor then to proceed continuously and hence relatively fast until the temperature error under correction has been brought back into the small-error range within which the step timer renders the motor operation intermittent as aforesaid.

4. In a steam generator, a furnace having a gas outlet and walls lined with water cooled tubes, burners for introducing into said furnace streams of fuel and air which create a mass of burning gas within the tube lined walls, a fluid heater carrying steam from the generator and receiving heat from the furnace gases which leave said outlet, a passage through which a portion of said furnace gases may by-pass around said heater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said fluid heater, forward and reverse driving means for said burner motor respectively activatable by said instrument when said leaving-steam temperature falls below and rises above a desired value and then effective respectively to adjust said burners in the upward and in the downward direction, forward and reverse driving means for said damper motor respectively activatable by said instrument when said steam temperature falls below and rises above said desired value and then effective respectively to adjust said damper in the closing and in the opening direction and control transfer means for causing said instrument to govern as aforesaid the said burner motor driving means at times and the said damper motor driving means at other times.

5. In a steam generator, a furnace having a gas outlet and walls lined with water cooled tubes, burners for introducing into said furnace streams

of fuel and air which create a mass of burning gas within the tube lined walls, a fluid heater carrying steam from the generator and receiving heat from the furnace gases which leave said outlet, a passage through which a portion of said furnace gases may by-pass around said heater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said fluid heater, forward and reverse driving means for said burner motor respectively activatable by said instrument when said leaving-steam temperature falls below and rises above a desired value and then effective respectively to adjust said burners in the upward and in the downward direction, forward and reverse driving means for said damper motor respectively activatable by said instrument when said steam temperature falls below and rises above said desired value and then effective respectively to adjust said burners in the upward and in the downward direction, forward and reverse driving means for said damper motor respectively activatable by said instrument when said steam temperature falls below and rises above said desired value and then effective respectively to adjust said damper in the closing and in the opening direction, and control transfer means responsive to changes in steam generator loading and functioning to cause said instrument to govern the aforesaid driving means for one of the aforesaid two motors when that loading is within a given range and to govern the aforesaid driving means for the other of those motors when the generator loading is outside of said given range.

6. In a steam generator, a furnace having a gas outlet and walls lined with water cooled tubes, burners for introducing into a given portion of said furnace streams of fuel and air which create a mass of burning gas within said tube lined walls, a superheater carrying the generated steam and receiving heat from the furnace gases which leave said outlet, a passage through which a portion of said furnace gases may by-pass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said superheater, forward and reverse control circuits for said burner motor activatable by said instrument when said temperature respectively falls below and rises above a desired value and then effective respectively to adjust said burners in the upward and in the downward direction, forward and reverse control circuits for said damper motor activatable by said instrument when said temperature respectively falls below and rises above said desired value and then effective respectively to adjust said damper in the closing and in the opening direction, and means for causing said instrument to govern as aforesaid the forward and reverse control circuits of said burner motor at times and the for-

ward and reverse control circuits of said damper motor at other times.

7. In a steam generator, a furnace having a gas outlet and walls lined with water cooled tubes, burners for introducing into a given portion of said furnace streams of fuel and air which create a mass of burning gas within said tube lined walls, a superheater carrying the generated steam and receiving heat from the furnace gases which leave said outlet, a passage through which a portion of said furnace gases may by-pass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said superheater, a first relay activated by said instrument when said temperature falls below a given desired value, a second relay activated by said instrument when said temperature rises above said value, forward and reverse operating circuits for said burner motor, forward and reverse operating circuits for said damper motor, means connecting said damper motor's forward and reverse operating circuits in control-receiving relation with said first and second relays whereby at certain times superheated steam temperature decreases below and increases above said desired value are corrected through compensating adjustments in the positioning of said damper, and means effective at other times and governed by the position of said damper for connecting said burner motor's forward and reverse operating circuits in control receiving relation with said first and second relays whereby during said other times superheated steam temperature decreases below and increases above said desired value are corrected through compensating adjustments in the tilting of said burners.

8. In a steam generator, a furnace having a gas outlet and walls lined with water cooled tubes, burners for introducing into said furnace streams of fuel and air which create a mass of burning gas within said tube lined walls, a superheater carrying the generated steam and receiving heat from the furnace gases which leave said outlet, a passage through which a portion of said furnace gases may by-pass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said superheater, forward and reverse control circuits for said burner motor activatable by said instrument when said temperature respectively falls below and rises above a desired value and then respectively effective to adjust said burners in the upward and in the downward direction, forward and reverse control circuits for said damper motor activatable by said instrument when said temperature respectively falls below

and rises above said desired value and then effective respectively to adjust said damper in the closing and in the opening direction, means for causing said instrument to govern as aforesaid the forward and reverse control circuits of said burner motor at times and the forward and reverse control circuits of said damper motor at other times, means responsive to the difference between said desired value of superheated steam temperature and the actual value thereof as registered by said instrument, and means governed by said difference-responsive means for causing the aforesaid corrective operations by said burner tilting and damper positioning motors to proceed with relatively rapid temperature adjusting effectiveness when said difference is large and with slower temperature adjusting effectiveness when said difference is small.

9. In a steam generator, a furnace having a gas outlet and walls lined with water cooled tubes, burners for introducing into said furnace streams of fuel and air which create a mass of burning gas within said tube lined walls, a superheater carrying the generated steam and receiving heat from the furnace gases which leave said outlet, a passage through which a portion of said furnace gases may by-pass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said superheater, a first relay activated by said instrument when said temperature falls below a given desired value, a second relay activated by said instrument when said temperature rises above said value, forward and reverse operating circuits for said burner motor, forward and reverse operating circuits for said damper motor, means effective as long as said damper occupies a given position such as that of minimum by-pass gas flow for connecting said burner motor's forward and reverse operating circuits in control receiving relation with said first and second relays whereby superheated steam temperature decreases below and increases above said desired value then cause the burner motor respectively to adjust the tilt of said burners as appropriate to correct the temperature, and means rendered effective when said burners reach a given position such as that of extreme downward tilt for connecting said damper motor's forward and reverse operating circuits in control receiving relation with said first and second relays whereby further undesired increases in superheated steam temperature then cause the damper motor correctly to adjust said damper in the by-pass flow increasing direction while subsequent undesired temperature drops produce corrective damper adjustment in the opposite direction until said given damper position is reached when said burner motor becomes reconnected for control by said first and second relays as aforesaid.

10. In a steam generator, a furnace having a gas outlet and walls lined with water cooled tubes, burners for introducing into a given portion of said furnace streams of fuel and air which create a mass of burning gas within said tube lined walls, a superheater carrying the gener-

ated steam and receiving heat from the furnace gases which leave said outlet, a passage through which a portion of said furnace gases may bypass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said superheater first and second relays selectively activated by said instrument when said temperature respectively falls below and rises above a desired value, forward and reverse operating circuits for said burner motor, forward and reverse operating circuits for said damper motor, means effective as long as said damper occupies a given position such as that of minimum by-pass gas flow for connecting said burner motor's forward and reverse operating circuits in control receiving relation with said first and second relays whereby superheated steam temperature decreases below and increases above said desired value then cause the burner motor respectively to adjust the tilt of said burners as appropriate to correct the temperature, means rendered effective when said burners reach a given position such as that of extreme downward tilt for connecting said damper motor's forward and reverse operating circuits in control receiving relation with said first and second relays whereby further undesired increases in superheated steam temperature then cause the damper motor correctively to adjust said damper in the by-pass flow increasing direction while subsequent undesired temperature drops produce corrective damper adjustment in the opposite direction until said given damper position is reached when said burner motor becomes reconnected for control by said first and second relays as aforesaid, means responsive to the difference between said desired value of superheated steam temperature and the actual value thereof as registered by said instrument, and means governed by said difference-responsive means for causing the aforesaid corrective operations by said burner tilting and damper positioning motors to proceed with relatively rapid temperature adjusting effectiveness when said difference is large and with slower temperature adjusting effectiveness when said difference is small.

11. In a steam generator, a furnace having a gas outlet and walls lined with water cooled tubes, burners for introducing into a given portion of said furnace streams of fuel and air which create a mass of burning gas within said tube lined walls, a superheater carrying the generated steam and receiving heat from the furnace gases which leave said upper outlet, a passage through which a portion of said furnace gases may bypass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting

movement to said by-pass damper, an instrument for registering the temperature of the steam leaving said superheater, forward and reverse control circuits for said burner motor activatable by said instrument when said temperature respectively falls below and rises above a desired value and then effective respectively to adjust said burners in the upward and in the downward direction, forward and reverse control circuits for said damper motor activatable by said instrument when said temperature respectively falls below and rises above said desired value and then effective respectively to adjust said damper in the closing and in the opening direction, means for causing said instrument to govern as aforesaid the forward and reverse control circuits of said burner motor at times and the forward and reverse control circuits of said damper motor at other times, a step timer effective to cause the aforesaid corrective operations by said burner tilting and damper positioning motors to proceed intermittently and hence relatively slowly as long as only a small difference exists between said desired value of superheated steam temperature and the actual value thereof as registered by said instrument, and means effective when said superheated steam temperature as registered by the instrument departs widely from said desired value for causing the accompanying corrective operation by the burner tilting motor or the damper positioning motor then to proceed continuously and hence relatively fast until the temperature error under correction has been brought back into the small-error range within which the step timer renders the motor operation intermittent as aforesaid.

12. In a steam generator, a furnace having a gas outlet and walls lined with water cooled tubes, burners for introducing into a given portion of said furnace streams of fuel and air which create a mass of burning gas within said tube lined walls, a superheater carrying the generated steam and receiving heat from the furnace gases which leave said outlet, a passage through which a portion of said furnace gases may bypass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said superheater, a first relay activated by said instrument when said temperature falls below a given desired value, a second relay activated by said instrument when said temperature rises above said value, forward and reverse operating circuits for said burner motor, forward and reverse operating circuits for said damper motor, means connecting said damper motor's forward and reverse operating circuits in control receiving relation with said first and second relays whereby superheated steam temperature decreases below and increases above said desired value cause the damper motor respectively to adjust said damper in the opening or by-pass flow raising and in the closing or by-pass flow lowering direction as appropriate to correct the temperature, means rendered effective when said damper reaches a first given position such as fully closed for con-

necting said burner motor's forward operating circuit in control receiving relation with said first relay whereby further undesired decreases in superheated steam temperature then cause the burner motor correctively to adjust said burners in the tilt raising direction, and means rendered effective when said damper reaches a second given position such as fully opened for connecting said burner motor's reverse driving circuit in control receiving relation with said second relay whereby further undesired increases in superheated steam temperature then cause the burner motor correctively to adjust said burners in the tilt lowering direction.

13. In a steam generator, a furnace having a gas outlet and walls lined with water cooled tubes, burners for introducing into a given portion of said furnace streams of fuel and air which create a mass of burning gas within said tube lined walls, a superheater carrying the generated steam and receiving heat from the furnace gases which leave said outlet, a passage through which a portion of said furnace gases may by-pass around said superheater and thereby cut down heat transfer thereto, a damper for adjusting the flow of said by-pass gases, means for tilting said burners whereby to alter the angle to the horizontal of the direction of said fuel and air streams so as to lower or raise the vertical location within the furnace of said burning gas mass, a motor for imparting tilt adjusting movement to said burners through said means, another motor for imparting position adjusting movement to said by-pass damper, an instrument for registering the temperature of the steam leaving said superheater, first and second relays selectively activated by said instrument when said temperature respectively falls below and rises above a desired value, forward and reverse operating circuits for said burner motor, forward and reverse operating circuits for said damper motor, means connecting said damper motor's forward and reverse operating circuits in control receiving relation with said first and second relays whereby superheated steam temperature decreases below and increases above said desired value cause the damper motor respectively to adjust said damper in the opening or by-pass flow raising and in the closing or by-pass flow lowering direction as appropriate to correct the temperature, means ren-

dered effective when said damper reaches a first given position such as fully closed for connecting said burner motor's forward operating circuit in control receiving relation with said first relay whereby further undesired decreases in superheated steam temperature then cause the burner motor correctively to adjust said burners in the tilt raising direction, means rendered effective when said damper reaches a second given position such as fully opened for connecting said burner motor's reverse operating circuit in control receiving relation with said second relay whereby further undesired increases in superheated steam temperature then cause the burner motor correctively to adjust said burners in the tilt lowering direction, means responsive to the difference between said desired value of superheated steam temperature and the actual value thereof as registered by said instrument, and means governed by said difference-responsive means for causing the aforesaid corrective operations by said burner tilting and damper positioning motors to proceed with relatively rapid temperature adjusting effectiveness when said difference is large and with slower temperature adjusting effectiveness when said difference is small.
